UNITED STATES PATENT OFFICE.

ANTON KOEBERLEIN, OF PHILADELPHIA, PENNSYLVANIA, ASSIGNOR TO
MORSE, WILLIAMS & CO., OF SAME PLACE.

ELEVATOR.

SPECIFICATION forming part of Letters Patent No. 497,922, dated May 23, 1893.

Application filed August 25, 1892. Serial No. 444,039. (No model.)

To all whom it may concern:

Be it known that I, ANTON KOEBERLEIN, of Philadelphia, Pennsylvania, have invented an Improvement in Elevators, of which the following is a specification.

5 My invention relates to elevators, and consists of certain improvements which are fully set forth in the following specification and are shown in the accompanying drawings which 10 form a part thereof.

15 My improved elevator or hoist is more particularly adapted for lifting kegs of beer or other liquors from a cellar or store room to an upper floor or bar, in a convenient and expeditious manner, but it may also be used for hoisting other articles.

20 My invention is designed to permit the loading and unloading of the platform with ease and expedition, rendering the lifting of 25 the barrel or keg from the floor wholly unnecessary.

25 My invention is also designed to permit the elevation of the keg or barrel to the desired position for use and to maintain the keg in such position while in use, permitting it to be 30 easily lowered and replaced by another when its contents have been discharged. By this means the handling of the keg, except in rolling it to and from the platform, is wholly dispensed with.

35 It is also an object of my invention to so support the keg or barrel upon the platform that its contents may be readily and fully drawn off.

40 While my invention is thus designed more especially for lifting liquors in barrels or kegs, and in supporting them in proper position while being used, it may also be employed for ordinary hoisting purposes.

45 The apparatus by which I accomplish these objects is more fully set forth hereinafter and illustrated in the drawings to which reference will now be made.

In the drawings:—Figure 1 is a side elevation of my improved elevator or hoist. Fig. 2 is a front elevation of the same. Fig. 3 is a similar view on an enlarged scale, and Fig. 4 is a sectional plan view on the line $x-x$ of Fig. 3.

A is the lower floor or ground. B is the 50 upper floor of the same building to which the articles are to be elevated, and is provided with the usual opening C. In the drawings I have shown this opening C located under a counter or bar D.

55 E, E, are vertical guides extending from the top to the bottom of the elevator shaft. These guides preferably extend down into a chamber or recess F in the floor A as shown in Fig. 1. For convenience and economy of 60 construction I prefer to construct the guides E, E, of channel iron as shown in Fig. 4. The guides E, E are thus provided with grooves.

G is the elevator platform which may be provided with a recess or seat a to support a 65 barrel or keg.

H, H, are arms carried by the platform G which are provided with idle rollers g running in contact with the guides E, E. I prefer to employ grooved rollers as shown, which 70 engage the flange e of the guides E, E. The arms H, H which carry the platform G constitute the guide frame of the elevator.

I, I, are grooved rollers carried by the arms H, H, which constitute cable or hoisting rope 75 guides.

J is a rope or cable connected at one end as at j, to the upper portion of the elevator shaft and passing thence down about the rollers I, I, and thence up over a guide roller 80 K located near the top of the shaft and thence down to the drum L. The rope or cable lies within the channel of the guides E, E, and the rollers I, I, may extend into the channel as shown in Fig. 4.

85 M is a brace bar between the arms H, H.

The drum L is carried on a shaft l journaled in a bracket N preferably adjacent to the lower floor A.

O is a counter shaft journaled in arms of 90 the bracket N adjacent to the drum L and provided with a crank P by which it may be rotated.

Q is a pinion on the counter shaft O by which power is imparted to the drum shaft l 95 through the gear R.

S is a ratchet wheel carried by the shaft O.

T is a pawl pivoted to the bracket r and en-

gaging the teeth of the ratchet wheel S to prevent backward rotation thereof.

U is a friction wheel carried by the shaft O.

V is a friction band or belt passing about 5 the friction wheel U and carried by a lever W by which the belt may be tightened or loosened upon the friction wheel U. While this particular form of brake device is preferable, it is obvious that it may be varied and 10 any other of the well known brake devices may be employed. I prefer to form the platform G with a slight inclination as shown, so that the keg or barrel will be tipped slightly, the better to permit the drawing off of the 15 contents.

I shall now describe the operation of the hoist. When it is desired to elevate a keg, barrel, or other object, the platform G is lowered and the article to be elevated is placed 20 upon it. By employing the recess or chamber F in the lower floor or ground, I am enabled to bring the platform G on a level with the floor, since the arms H, H, may descend upon the guides E, E, within the chamber, and 25 the keg or barrel may then be rolled directly upon the platform and placed in position without the necessity of lifting it. I am thus enabled to bring the platform on a level with the floor while having the arms H, H, located below 30 the platform, which is very desirable, since when so located the platform is free and unobstructed and less elevation of the guides is required at the upper portion, so that the keg may be brought on a level with the counter 35 or under the bar without extending the guides above it. When the keg or other article is placed upon the platform G the pawl T is thrown out of engagement with the ratchet and the drum L is rotated through the crank 40 P, shafts O and l and gears Q, R, winding up the rope or cable J and elevating the platform G and its load. When the platform has been elevated to the desired position, the pawl T may be thrown into engagement with 45 the ratchet wheel, and the platform will be locked in its elevated position. The platform may be left in this elevated position while the contents of the keg are drawn off, and when the keg is emptied, the pawl and 50 ratchet may be thrown out and the elevator may be allowed to descend, the descent being controlled by the brake device. The emptied keg may be removed and another may be placed upon the platform and elevated as before.

In Fig. 2 of the drawings, I have shown the

bar or counter D provided with an aperture d in its top, through which the keg may be lifted while on the platform.

While I prefer the details of construction 60 shown, I do not mean to limit myself to them as it is apparent that they may be modified without departing from the invention.

What I claim as new, and desire to secure by Letters Patent, is—

1. In an elevator or hoist, the combination with elevator guides, of an inclined platform provided with a central recess or seat a to support a barrel upon its end in an inclined position, a guide frame guided by the elevator guides and carried by the inclined platform extending downward below it so as to leave the upper surface of the inclined platform wholly unobstructed, and power devices to raise and lower the platform with its guide 70 frame.

2. In an elevator or hoist, the combination of the vertical grooved guides E, E, the guide arms H, H guided on the guides E, E, the idlers I, I carried one by each of the arms H, H and projecting into the grooves of the guides E, the platform carried by the arms H, H, and the hoisting rope passing about the idlers I, I and lying within the grooves of the guides E, E.

3. In an elevator or hoist, the combination of the vertical grooved guides E, E, the guide arms H, H the guide rollers carried thereby and running on the edges of the guides, the idlers I, I carried by the arms H, H and projecting into the grooves of the guides E, the platform carried by the arms H, H, and the hoisting rope passing about the idlers I, I and lying within the grooves of the guides E, E.

4. In an elevator or hoist, the combination 95 of the vertical grooved guides E, E, the guide arms H, H guided on the guides E, E, the idlers I, I carried by the arms H, H one on each side and projecting into the grooves of the guides E, E, the guide rollers g, carried by 100 the arms H, H running on the guides E, E, and located on each side, above and below the idlers I, I, the platform carried by the arms H, H, and the hoisting rope extending vertically within the grooves of the guides E, 105 E, and passing about the idlers I, I.

In testimony of which invention I have hereunto set my hand.

ANTON KOEBERLEIN.
